DECATIZING CYLINDER

Gustav G. Hennig, Paterson, N. J., assignor of
one-half to C. Frederick Hennig, Paterson,
N. J.

Application February 11, 1948, Serial No. 7,551

2 Claims. (Cl. 68—8)

1

My invention relates to treating textile material or cloth and more particularly to decatizing cylinders about which the cloth is wound for treatment.

In the steam treatment of textile material or cloth, it is customary to wind a blanket and the cloth about the peripheral wall of a decatizing or steaming cylinder in order that steam from within the cylinder may be applied to the cloth through perforations formed in the treating zone of the peripheral wall. Should water, occasioned by the condensation of steam within the cylinder, seep through the perforations and engage the cloth, a spotting or discoloration of the cloth would occur and thus depreciate the value of the cloth, the sections thus spotted or damaged being removed and discarded. One solution to the problem of preventing damage of this character to the cloth is to provide the cylinder with a plurality of radially extending tubes having their outer ends threaded into the perforations and with the tubes being of a length to position their inner ends above the level of any water which accumulates in the cylinder to preclude leakage of water through the tubes, an example of constructions of this character being disclosed in U. S. Patents Nos. 364,593, 1,047,683 and 2,085,222.

However, inasmuch as each of the perforations in the peripheral wall has to be tapped and the end of the tube for insertion therein threaded, in order to effect a rigid and tight fit, it will be apparent that a decatizing cylinder thus fabricated is extremely expensive not only in initial construction, but with respect to maintenance in the replacement of tubes which often become damaged and/or have their outer ends broken and remaining in the perforations.

One of the objects of my invention is to provide a decatizing cylinder which is constructed and arranged in a manner as to eliminate the aforementioned water baffle tubes and at the same time preclude seepage of water from within the cylinder into engagement with the cloth being treated.

Another object of my invention is to provide a decatizing cylinder of the foregoing described character which is simple in construction, durable in use, efficient in operation and economical in manufacture and maintenance.

With the above and other objects in view, as will hereinafter appear, the invention consists in the combination and arrangement of parts hereinafter set forth and illustrated in the accompanying drawings from which the several features of the invention and the advantages at-

2

tained thereby will be readily understood by those skilled in the art.

Referring to the drawings wherein like reference characters designate like parts throughout the several views:

Figure 1 is a longitudinal sectional view of a decatizing cylinder constructed in accordance with my invention, the arms for supporting the steam chest being transversely transposed for 10 clarification.

Figures 2 and 3 are sectional views taken on the lines 2—2 and 3—3 of Figure 1, respectively.

Figure 4 is a longitudinal sectional view of the cylinder illustrating a modified construction.

15 Figure 5 is a sectional view taken on the line 5—5 of Figure 4.

In practicing my invention, as illustrated in Figures 1 to 3 inclusive in the drawings, I provide a decatizing cylinder 5 for use in conjunction with 20 apparatus for treating textile material or cloth and which cylinder comprises a hollow cylindri-form body having a circumferential wall 6 and sinistral and dextral end walls 7 and 8, the end walls 7 and 8 serving to seal the respective ends 25 of the body and having fixed thereto centrally disposed bearing seals 9 and 10, respectively. The seal 9 has extending therethrough and in fixed relation thereto a tubular member 11 constituting a shaft which is rotatably mounted in a station- 30 ary bearing member 12, while a steam conduit 13 extends through the seal 10 in fixed relation therewith and constitutes a shaft which is rotatably mounted in a stationary bearing member 14, thus, permitting rotation of the cylinder relative to the members 12 and 13.

40 Disposed within the cylinder 5, in spaciality with the walls 6, 7 and 8, is a cylindrical steam distributing chest defined by a circumferential wall 15 and end walls 16. The ends of the wall 15 are provided with flanges F secured to the circumjacent margins of the walls 16 by means of nuts and bolts or the like. The walls 16 are connected to rings R, secured to the inner peripheral face of the wall 6 by means of spaced arms 17 45 whereby the chest is maintained in the aforesaid spaciality. Each of the walls 16 is provided with a plurality of ports 18 for permitting the passage of steam from within the chest to within the end sections of the cylinder 5, the conduit 13 extending into the chest, through the adjacent wall 16, for introducing steam into the chest as herein-after more fully described.

50 In close proximity to the walls 7 and 8, the inner peripheral face of the wall 6 of the cylinder 5 has secured thereto a pair of baffle rings 19 and

20 which define a material treating zone about the cylinder with the peripheral wall being perforated as at 21 throughout the length and width of the zone. The rings 19 and 20 coact with the walls 7 and 8 to define sinistral and dextral condensing chambers 22 and 23 within the end sections of the cylinder, respectively, and with each other to define a dry steam chamber 24 between the chambers 22 and 23 and about the peripheral wall 15 of the steam chest for supplying steam to textile material, wound about the treating zone, through the perforations 21 according to customary practice.

The end walls 7 and 8 are each provided with a drain cock 25 for draining liquid, occasioned by the condensation of steam, from the chambers 22 and 23. The tubular member 11 extends through the adjacent wall 16 of the steam chest and is provided therein with a pair of lateral branches or pipes 30. The outer ends of the pipes 30 are provided with scoops or buckets 31 each being provided with a baffle partition 32 at its lower end whereby liquid or water lifted therein will drain through the pipes 30 towards the member 11 and not be discharged through the opposite side of the respective scoop, it being understood that the tubular member is longitudinally and centrally divided by a partition 33 to provide a pair of compartments communicating with the pipes 30 respectively. As the cylinder, steam chest and scoops 31 rotate in unison, it will be apparent that any liquid, for instance, water condensed from steam, within the bottom of the chest will be scooped therefrom and discharged through the member 11.

In operation—assuming a blanket and textile material is wound about the treating zone of the cylinder in the usual manner—steam is introduced into the steam chest through the conduit 13 and thence passes into the chambers 22 and 23 through the ports 18, the steam, thus introduced into the chest, at the same time effects heating of the peripheral wall 15 of the chest and water, produced by condensation within the chest, is discharged by means of the scoops 31 through the tubular member 11 during rotation of the cylinder. Steam from the chambers 22 and 23 passes into the chamber 24, between the circumferential faces of the baffle rings 19 and 20 and the peripheral wall 15 of the steam chest and thence through the perforations 21 of the wall 6 to treat the material disposed thereabout, it being understood that the heated surface of the wall 15 effects drying of the steam within the chamber 24 to preclude condensation therein and thus eliminate spotting or discoloration of the textile material being treated.

If desired, and as illustrated in Figures 4 and 5 of the drawings, siphoning means may be provided for siphoning the water from the chest and the chambers 22 and 23. In a construction of this character, the tubular member 11 and scoops 31 have substituted therefor a siphoning pipe 40 which constitutes a shaft which extends through the sinistral end walls 7 and 16 of the cylinder and chest and which pipe 40 is provided with a T 41 to which is secured a tube 42 for siphoning water from the chamber 22. The inner end of the pipe 40 is provided with an elbow 43 having connected thereto a tube 44 for siphoning the water from within the chest. The seal 10 has extending therethrough a stationary bearing member 45 which in turn has extending therethrough and in fixed relation therewith the conduit 13 and a siphoning tube 46 which terminates within the cham-

ber 23, it being understood that the tube 46 and pipe 40 are connected to suitable siphoning means effective for removing the water from the steam chest and the chambers 22 and 23 when rendered operative.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined to the herein described use therefore as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In a decatizing cylinder construction, a hollow closed cylindrical body having peripheral and end walls, a pair of spaced radial partitions disposed within said body and secured to said peripheral wall in spaced relation to said end walls and with each partition being provided with a central opening, a steam chest secured within said body and extending through said openings in spaced relation with said end walls and coacting with the latter and said partitions to define condensing chambers at the ends of said body and a steam chamber between said condensing chambers, said steam chest having circumferential and end walls with the latter being provided with outlet ports communicating with said condensing chambers for supplying the latter with steam from said chest, said circumferential wall being coextensive with said steam chamber for drying steam in said steam chamber by heat radiated from said circumferential wall, said latter wall being spaced from said partitions and coacting therewith to define steam passages between said steam chamber and said condensing chambers whereby steam emitted into said condensing chambers through said ports passes into said steam chamber, said peripheral wall being formed with perforations between said partitions and communicating with said steam chamber for defining a cloth treating zone about said body for treating material disposed about said zone by steam from said steam chamber, and condensate removing means extending into at least one of said chambers for removing liquid from within said body.
2. In a decatizing cylinder construction; a hollow closed cylindriform body having a peripheral wall and end walls fixed to said peripheral wall; steam supply means suspended within said body in fixed and spaced relation with said walls; spaced baffle rings transversely disposed within said body and fixed to said peripheral wall in spaced relation with said end walls; said rings surrounding said supply means in circumjacent spaciality therewith and coacting with said supply means and said body to define condensing chambers adjacent said end walls, respectively, and a steam chamber surrounding said supply means and disposed between and in communication with said condensing chambers; said steam supply means being provided with outlet ports

communicating with said condensing chambers for emitting steam from said supply means into said steam chamber through said condensing chambers and between said rings and said supply means, whereby, steam in said steam chamber is capable of being dried by heat radiated from said supply means; said peripheral wall having a cloth treating zone about said steam chamber and formed with perforations opening directly into said steam chamber to permit passage of steam from said steam chamber to material disposed about said zone.
